Frances N. Farwell,
Inventor,
By Frank A. Kenan,

UNITED STATES PATENT OFFICE.

FRANCOIS N. SAVARD, OF AVON, MASSACHUSETTS.

HEATER FOR BOX TOES.

Application filed March 10, 1923. Serial No. 624,805.

To all whom it may concern:

Be it known that I, FRANCOIS N. SAVARD, a citizen of the United States of America, and resident of Avon, in the county of Nor-
5 folk and State of Massachusetts, have in-
vented certain new and useful Improve-
ments in Heaters for Box Toes, of which
the following is a specification.

This invention relates to steam heaters for
10 leather to be shaped to form box toes to be
used during the manufacture of shoes in the
lasting process, and it has for an object
the provision of novel means for subjecting
the leather for box toes to the action of
15 steam heat, without liability of injuring the
boxing or burning the leather as would be
the case if steam were allowed to escape and
come in contact with the boxing, or leather.

It is a further object of this invention to
20 produce an oven in which provision is made
for subjecting boxings to the action of
steam heat, and in which the heating device
will subject the boxing to the action of heat
uniformly.

25 It is a further object of this invention to
produce a heating oven for the purpose in-
dicated, comprising comparatively few in-
expensive parts which can be expeditiously
manufactured and assembled.

30 With the foregoing and other objects in
view, the invention consists in the details
of construction, and in the arrangement and
combination of parts to be hereinafter more
fully set forth and claimed.

35 In describing the invention in detail,
reference will be had to the accompanying
drawings forming part of this application,
wherein like characters denote correspond-
ing parts in the several views, and in
40 which—

Figure 1 illustrates a front elevation of
the oven embodying the invention;

Figure 2 illustrates an end view thereof;
and

45 Figure 3 illustrates a sectional view on
the line 3—3 of Fig. 1.

In these drawings 5 and 6 denote the
upper and lower oven sections respectively,
and except for the frames 7 and 8 which

support the lower section, the said sections 50
are of identical construction.

Each section comprises a rectangular
hollow steam chest which will admit of the
circulation of steam therethrough. The sec-
tion 5 has a steam supply pipe 9 and a 55
steam exhaust pipe 10, whereas the section 6
has a steam supply pipe 11 and a steam ex-
haust pipe 12, the said pipes entering the
said sections through their ends, preferably,
in order that the steam may circulate and 60
heat the sections uniformly. The said sec-
tions have apertured lugs 13 and 14 re-
spectively, projecting from their rear sides,
and these lugs are secured together by a
fastening 15 such as a screw or any other 65
appropriate binding or fastening device, and
the said sections have lugs 16 and 17 re-
spectively, at their ends secured together by
fastenings such as 15 heretofore described.

The section 5 has flanges 18 and 19 at its 70
ends and a flange 20 at its rear, and the sec-
tion 6 has flanges 21 and 22 at its ends and
a flange 23 at its rear, the end and rear
flanges of the said members being adapted
to abut or engage each other to hold the 75
bottom wall of the section 5 in spaced rela-
tion to the upper wall of the section 6, so
as to form an intervening space or oven for
the reception of the boxing which is to be
heated. 80

Owing to the fact that each steam chest
is formed by walls that are integral, there
are no joints through which steam can
escape to impair the boxing or leather, and
a device has been operated successfully in 85
practice and has given better results than
devices heretofore known intended for the
same general purpose.

At the exhaust end of the chests it would
also be desirable to supply check valves A 90
which will serve to retain the steam pressure
but allow the condensed water to escape.

When the leather boxing for a shoe is to
be heated, steam is supplied to the heater and
the leather in its flat state is inserted between
the two ovens in the space formed by the
flanges and the heat is effective to soften
the material employed for stiffening the 95

leather, thus making the leather more pliable in order that it may be applied to the last to form the boxing.

I claim:

5 In an oven for heating leather shoe boxings, substantially rectangular chests for the reception of steam, supply and exhaust pipes connected to the said chests, the said chests having coinciding and engaging flanges on

their ends and rear sides, respectively, at 10 their bottom and top, whereby a space is formed between the chests when the flanges are in engagement with one another, and means for clamping the chests in engagement with each other with their flanges in 15 engagement, substantially as described.

FRANCOIS N. SAVARD.
